L. D. GREGG.
JOURNAL BEARING.
APPLICATION FILED DEC. 2, 1918.

Patented Oct. 4, 1921.

By Mano, Cameron, Lewis & Massie,
Attorneys.

UNITED STATES PATENT OFFICE.

LOUIS D. GREGG, OF HACKENSACK, NEW JERSEY, ASSIGNOR TO THE GREGG COMPANY, LIMITED, OF HACKENSACK, NEW JERSEY, A CORPORATION OF NEW YORK.

JOURNAL-BEARING.

1,392,636.

Specification of Letters Patent.

Patented Oct. 4, 1921.

Application filed December 2, 1918. Serial No. 265,014.

To all whom it may concern:

Be it known that I, LOUIS D. GREGG, a citizen of the United States of America, and a resident of Hackensack, New Jersey, whose post-office address is % The Gregg Company, Ltd., Hackensack, N. J., have invented a new and useful Improvement in Journal-Bearings, which invention is fully set forth in the following specification.

10 Although the present invention is applicable to various services, yet it is intended primarily for providing a reliable bearing for the end-thrust of car-wheel journals. The object of the invention is to provide an efficient journal-box, with a removable pillow-block or bearing, and a positive end-thrust bearing, while permitting ready access to the interior of the box, as for lubrication or other purpose. The invention 15 comprises the provision, upon the journal-box, of one or more fixed bearing-surfaces, and the employment therewith of a cover or cap which can receive the end-thrust of the journal and transmit the same positively and 20 directly against the fixed surface or surfaces aforesaid, and yet is readily disengageable therefrom. The invention further comprises provision for inserting and retaining the half-bushing or pillow-block for the 25 journal; also, an improved form of automatic latch for retaining the cap in its closed position, for permitting it to be readily lifted or opened, and for maintaining it in its opened position; and, finally, such details of construction and arrangement as are 30 hereinafter set forth in the appended claims.

The invention is susceptible of embodiment in various concrete forms; yet, for the sake of clearness, one preferred embodiment 40 is illustrated in the annexed drawings and will now be described. In these drawings:

Figure 1 is a longitudinal vertical section through the new journal-box, showing the journal and the pillow-block in position and 45 the thrust-bearing cap closed.

Fig. 2 is a similar view of a detail, showing said cap in open position; and

Fig. 3 is an end-view of the journal-box, with the journal removed, the cap omitted, 50 and the pillow-block dropped down.

The outer portion of the car-axle is represented at 1; and at 2 is shown its cylindrical spindle or journal, of unvarying diameter, and with no shoulder or collar. 3 55 represents the new journal-box as a whole; and 4 is the usual pedestal integral there-

with, for supporting the car-body. The journal-box is chambered out; the lower portion of the chamber affords a space for lubricating-waste, etc., and the upper portion 60 a block-receiving space, whose roof is indicated (by dotted lines, in Fig. 3) as squared or otherwise non-cylindrical, to prevent angular movement of the pillow-block. The inner end of the journal-box is apertured to receive the journal, the aperture being slightly enlarged vertically (as usual) to permit the usual vertical play. The outer end of the journal-box is open, and is provided with the upturned lower lip 5, which 65 constitutes a substantially-vertical (yet slightly in-turned) bearing-surface. Preferably, another upturned lip 6 may rise from the outer end of the upper surface of the box, to provide a second vertical bearing-surface. 70

On each side of the upper portion of the chamber is a sloping guide-way or ledge 7; at the inner end is the down-turned flange or shoulder 8; and near the outer end is the 80 depending lug or shoulder 9. 10 is the pillow-block, a half-bushing, with its top and sides shaped to fit into the upper portion of the chamber, while its lower surface is cylindrically concaved to fit upon the journal. This block 10 is inserted through the 85 open outer end of the journal-box, along the guides 7, to clear shoulder 9 and abut against shoulder 8; and the whole is then applied upon the journal, as shown in Fig. 1, the shoulder 9 thereafter retaining the block in place even when the end-cap is removed (as 90 in Fig. 2). The sloping guide-ways 7 are parallel to each other and lie in the same sloping plane; their inner ends rise to such 95 level as to support the inner end of the pillow-block in fairly snug contact with the roof of its chamber; while their outer ends are sufficiently below the overhanging lug 9 to permit the removal or insertion of the 100 block when the spindle is not in place. To remove the pillow-block (when broken or worn), the spindle and journal-box are first disassembled, whereupon the pillow-block drops down (to rest upon the two guide-ways 7), and can be drawn out from the 105 box; thereafter a new block is inserted in position being guided to its inner position by the guides 7, and then temporarily held from coming out, until the spindle and journal box have been reassembled.

The new thrust-bearing cap 11 is shaped

to fit over the outer end of the journal-box and cover its opening, and is provided with a groove to receive the retaining-lip 5, and another groove to receive the retaining-lip 6 (when present). The face of said cap is shown as dished, to extend into the chamber, in position to receive the end-thrust of the journal; and its lower portion has a curving surface or cam, to ride over the lip 5 as the cap is closing. The cap may be pivoted or otherwise secured upon the box in any convenient manner, so long as sufficient vertical movement is permitted to disengage the retaining-lip or lips. But preferably the cap continues in an upper portion which is somewhat narrowed, to enter between two identical up-standing pivot-lugs 12, which rise from the outer end of the box; and a pivot-pin or bolt 13 is passed through the two lugs and through a vertically-slotted opening in the adjacent portion of the cap. Also preferably, this portion of the cap is enlarged to provide the groove for the lip 6, and a cam-shoulder to ride over said lip 6, when the cap is closing; and the slotted opening may be enlarged for receiving a spring. Preferably this spring may be primarily of hair-pin shape, with its two members formed into helixes that surround the pin, as indicated in Fig. 3; in which case the loop (constituting the middle of the spring) is seated within the recess or enlargement 14 in the head of the cap, while the two ends 15 bear against any convenient portion of the box, as indicated in Figs. 1 and 2. The tension of the spring tends to force the upper portion of the slot toward the pin, and to maintain the grooves of the cap in engagement with the lips of the journal-box.

As seen in Fig. 1, end-play of the journal 2 will abut against the inner face of the cap 11; and this thrust is met by the direct and positive opposition of the fixed bearing-surfaces 5 and 6, which maintain the cap firmly and securely against horizontal displacement. The new construction relieves the pivot-pin of the strain, which is borne entirely by the two integral lip-portions of the journal-box itself.

To obtain access to the interior of the journal-box, it is only necessary to raise the cap a slight distance vertically (against the tension of the spring, when present), sufficient to disengage the retaining-lip or lips, as indicated by dotted lines to Fig. 1, and then to swing the cap outward, into the open position indicated by Fig. 2, whereupon the spring forces the cap outward (with its shoulder resting upon lip 6) and maintains the cap in its raised position. To restore the cap, it is only necessary to force it slightly inward (against the spring-pressure), so as to unseat the upper shoulder (when present); whereupon the spring forces the cap down, back into its closed po-

sition, the cam-surface or surfaces lifting the cap over the lip or lips, and then permitting the spring to force the grooves down into engagement and maintain the cap in closed position, as before.

70

It will be understood, of course, that the invention is not limited to the precise construction and arrangement set forth, but can be embodied in various forms. It is obvious that some of the features might be omitted, 75 certain parts might be transposed or inverted, and that other modifications will readily occur to persons skilled in the art. For example: only one retaining lip, as 5, might be provided; an ordinary slot-and-pin connection might be employed, either with or without a spring; the pin might be carried by the cap, while the lugs 7 are slotted; a positive pivot might be dispensed with, and a spring alone relied on to maintain the catch-members in engagement; or some other form of spring might be employed, or the spring even omitted altogether and gravity relied on to take its place; but the construction set forth in detail has proved extremely satisfactory, and is therefore preferred.

80

Having thus fully described the invention, what is claimed is:

85

1. The combination of an open-ended journal-box whose chamber has a non-cylindrical upper portion with two inclined guide-ways and two depending shoulders, and a removable bearing-block resting upon the inner ends of said guides and located between 100 said shoulders.

95

2. The combination of an open-ended journal-box whose chamber has a non-cylindrical upper portion with two inclined guide-ways and two depending shoulders, 105 the spindle of a car-axle located in said box, a removable bearing-block resting upon the inner ends of said guides and located between said shoulders to rest upon said spindle, and releasable means for closing the 110 end of said box and affording an end-bearing for the end of said spindle.

105

3. The combination of an open-ended journal-box whose chamber has an inclined 115 guide-way and a depending-shoulder, and a removable bearing-block resting upon the inner end of said guide and adjacent said shoulder.

115

4. The combination of an open-ended journal-box whose chamber has an inclined 120 guide-way and a depending shoulder, a removable bearing-block resting upon the inner end of said guide and located adjacent said shoulder to rest upon said spindle, and a releasable cap for closing the end of said 125 box and affording an end-bearing for the end of said spindle.

125

In testimony whereof I have signed this specification.

LOUIS D. GREGG.
